Inventor:

Harriet Lyons Redmond

by *Harriet Lyons Redmond*
Attest,

UNITED STATES PATENT OFFICE.

HARRIET LYONS REDMOND, OF BOSTON, MASSACHUSETTS, ASSIGNOR TO THE WILLIAM CARTER COMPANY, OF NEEDHAM HEIGHTS, MASSACHUSETTS, A CORPORATION OF MASSACHUSETTS.

UNDERGARMENT.

1,414,206.

Specification of Letters Patent. Patented Apr. 25, 1922.

Application filed April 11, 1921. Serial No. 460,220.

To all whom it may concern:

Be it known that I, HARRIET LYONS REDMOND, a citizen of the United States, and a resident of Boston, in the county of Suffolk and State of Massachusetts, have invented an Improvement in Undergarments, of which the following description, in connection with the accompanying drawings, is a specification, like characters on the drawings representing like parts.

This invention is an improvement upon the construction shown in my patent issued in my then name, Harriet R. Lyons, No. 1,364,058, dated December 28, 1920, and relates to wearing apparel, the principal object of the invention being to provide an undergarment especially designed for use by women and adapted to be worn beneath the corset, whereby the body of the wearer will be shielded from the corset, thus preventing the rubbing or abrasion of the flesh.

A further object of the invention is to provide an undergarment having approved means thereon to permit engagement of the same with the stocking supporters of the wearer in such a way that it will be held in its intended position and will prevent all abrasive action of the corset upon the flesh.

A further object of the invention is to improve the upper portion of the garment, particularly with reference to the part under the arms and at the bust.

In the drawings,—

Fig. 1 is a side elevation representing the garment of the invention in use;

Fig. 2 is a front elevation of the garment shown in Fig. 1;

Fig. 3 represents in side elevation the extensions upon the two opposite sides of the garment at the lower edge thereof; and

Fig. 4 is a vertical sectional view representing the preferred mode of use of the garment with respect to the stocking supporters.

Referring more particularly to the drawing, the body of the garment is indicated at 1. It is intended to be worn next the flesh and is desirably of knitted material comprising a front piece 2 and a back piece 3, which are united down each side by two seams, one of which is indicated at 4, the said seams extending throughout the entire length or vertical extent of the garment. While within the scope of my invention, the

garment may be made in a single integral piece, it is preferably constructed as described. Desirably it is hemmed at its upper edge as indicated at 5 and at its lower edge as indicated at 6. At each side of the garment at its lower end, the front and back pieces 2, 3 are tapered to a relatively sharp point, and the edges are hemmed as indicated at 7, 8, being folded upon themselves, so that the line of stitching 9 substantially overlies the line of the seam 4, so as to reenforce the strap-like member 10 that is thus provided. The extreme lower end of each hem portion 7, 8 is folded upon itself as indicated at 11, 12, so as to provide a reenforced tip, and the hemming 9 is such as to provide a button-hole 13 that is surrounded by the hem-stitching and is reenforced thereby. The result is a narrow, long extension 10 of very great strength and adapted to receive the stocking supporter depending from the corset. The corset of the wearer is indicated at 14. From each side thereof depends the stocking fastener 15 comprising a strip 16 having a button-like member 17 and a metal piece 18 which is adapted to secure the upper end 80 of the stocking 19 over the button 17.

In use, the corresponding extension 10 is folded about the lower end of the stocking supporter 16, as indicated in Fig. 4, and the button 17 is passed through the button-hole 13, all as fully described in my said patent. While I have set forth in my said patent that at each side of the garment at its lower edge, one or a plurality of tab-like extensions may be provided, I have herein disclosed an improved construction of such extension.

The upper portion of the garment is provided at each side beneath the arm with a reenforce 20. This is desirably an additional piece of substantially semi-circular shape and of knitted material corresponding in elasticity, texture and other characteristics with that used for the garment 1. It is seamed, as indicated at 21, to the garment. I am aware that heretofore garments have been made with reinforcements beneath the arms. They have not, however, been satisfactory, mainly owing to the position or point at which they are placed. It will be observed, viewing Fig. 1, that the main portion of the reinforcing piece 20, which desirably overlies the body of the gar-

ment rather than underlying the same, is in front of the line of the seam. The purpose of this is to guard against the wear which comes upon the garment between the 5 arm of the wearer when moved to and fro and the body. Heretofore so far as I am aware, the garment has worn in front of the reenforce, because no provision has been made to guard against the wear that is occasioned between the arm when moved to 10 and fro and the body.

The garment is provided with a draw string or tape indicated at 22 received in a seam or pocket 23, another draw string 15 24 being provided within the hem 5 at the top of the garment. The garment at its upper edge is provided with a straight line, but the front portion of the garment 25 above the tape 22 is of greater vertical extent than the rear portion 26 thereof, as 20 will be evident from Figs. 1 and 2. This provides for the proper fit of the garment over the bust, in a manner that will be readily understood from the drawing. The 25 garment is desirably provided with shoulder straps 27, which are secured to the upper hem 5.

Having thus described one illustrative embodiment of my invention, I desire it to be understood that although specific terms are employed, they are used in a generic and descriptive sense and not for purposes of limitation, the scope of the invention being set forth in the following claims.

35 Claims.

1. As an article of manufacture, an undergarment adapted to be worn beneath the corset and having at its lower end at each 40 side a single tab-like extension having substantially parallel sides and of relatively great length compared to its width, said extension being reenforced along its longitudinal medium line and provided with means for detachably engaging the button

of the stocking supporter extending from 45 the corset.

2. As an article of manufacture, an undergarment adapted to be worn beneath the corset and comprising front and back members secured by longitudinally extending 50 seams at the sides of the body, said front and back members each having acutely shaped or pointed extreme lower ends at either side thereof, the adjacent ends of said front and back members being in juxtaposition and united for the greater portion of their length and hemmed to provide a centrally seamed longitudinal extension 10 having substantially parallel sides and of relatively great length compared with the 60 width, said adjacent ends being spaced near the bottom thereof to provide a button hole for the reception of a button of the stocking supporter depending from the corset.

3. An undergarment having at the upper 65 portion a reenforcement seamed to the outer surface of the garment beneath the arms, the reenforcements having the major portion thereof in front of the side median line of the garment so as to protect the same against 70 abrasion in the movement of the wearer's arms against the body said reenforcement being formed of material corresponding in elasticity to that of the body portion.

4. An undergarment having an upper portion provided with substantially semi-circular reenforcements of material corresponding in elasticity to that of said upper portion, the major part of each reenforcement lying in front of the side median line of the 80 garment, said reinforced upper portion being of greater vertical extent at the front than is the corresponding part at the back, thereby to provide for an accurate fit of said reinforced upper portion over the bust. 85

In testimony whereof, I have signed my name to this specification.

HARRIET LYONS REDMOND.
